PROPORTIONAL VALVE

Filed May 23, 1929

UNITED STATES PATENT OFFICE

GEORGE F. NAAB AND GEORGE R. BROWN, OF CLEVELAND, OHIO, ASSIGNORS TO THE NCRTH AMERICAN MANUFACTURING COMPANY, OF CLEVELAND, OHIO, A CORPORATION OF OHIO

PROPORTIONAL VALVE

Application filed May 23, 1929. Serial No. 365,368.

This invention relates to valve means for controlling gas burners and more particularly to so-called proportioning control units wherein the proportion of air and gas flow to a burner may be adjusted as by adjustment of either air or gas flow independent of the flow of the other for effecting the proper combustion conditions; and wherein flow to the burner may thereafter be controlled from zero to maximum without affecting the proportion.

This invention contemplates in such a unit air valve means adapted for arrangement in the air supply line and gas valve means adapted for arrangement in the gas supply line whereby these lines may be carried separately up to the burner so that neither line carries explosive mixture yet both may be controlled as a single line. Such a burner supply arrangement is another object of this invention.

The invention also contemplates an arrangement of the parts whereby the maximum gas valve opening may be adjusted without interruption to flow in the gas line; and similarly whereby air flow opening adjustment may be had without interruption to air flow.

A further object of our invention is to provide a unit valve assembly wherein friction during operation is reduced to a minimum yet providing a seal for the gas controlling parts.

The exact nature of our invention together with further objects and advantages thereof will be apparent from the following description taken in connection with the accompanying drawing in which Fig. 1 shows in elevation a burner and control unit installation of the improved type made possible by our invention; Fig. 2 is a sectional elevation through the control unit as in a plane parallel to that of Fig. 1; Fig. 3 is a sectional elevation of the parts appearing in Fig. 2 taken in a plane at right angles thereto; Fig. 4 is a plan view of parts appearing in Figs. 2 and 3; and Fig. 5 is a horizontal section as in the plane of line 5—5, Fig. 2.

With reference now to the drawing, 1 is a casing, having a dome portion 2 at its upper

end, therebelow opposed air inlet and outlet openings 3 and 4 respectively preferably flanged as indicated for connection in an air supply line for a gas burner, and having a mouth opening downwardly below the openings 3 and 4. The casing 1 is generally cylindrical in horizontal section so that the dome and those portions between the openings 3 and 4 have cylindrical walls, the mouth 5 being therefore circular. 55

The mouth 5 of the casing is closed by the flange portion 6 of a cover member 7 which cover member extends downwardly and centrally from the casing 1 and has a cylindrical cavity 8 opening downwardly. A cap 65 closure 9 is threaded into the mouth of the cavity 8. The member 7 is provided with lateral openings 10 and 11 for gas inlet and outlet to the cavity 8 as will appear. 70

It will be apparent that the parts 1, 7 and 9, in their illustrated assembly comprise casing means having a pair of chambers and inlet and outlet openings for each chamber. The larger and upper of said chambers is adapted for arrangement in the air supply line 12 to a gas burner 13 and the lower and smaller chamber for arrangement in the gas supply line 14 to the same burner; as indicated in Fig. 1 wherein the burner is of well-known siphon elbow type having air and gas inlet connections 15 and 16 respectively at 90°, a butterfly air valve 17 being associated with the nozzle air inlet and a globe type gas valve 18 being associated with the nozzle gas inlet, suitable other pipe fittings being employed for effecting the described connections as indicated. It will be apparent that the lines 12 and 14 may be as long as desired and may include fittings other than those shown and suitable to the installation. 80 85 90

As shown in the drawing the inlet and outlet openings 3 and 4 of the proportioning unit are at right angles to the gas inlet and outlet openings 10 and 11 so that elbows 19 are included in the line 14 to bring this line parallel with the line 12. The air and gas openings of the proportioning unit may, however, be parallel, obviously without departure from the scope of this invention. 95

Fitting within the cavity 8 is a valve 20 100

having a transverse through opening 21 and rotatable to register with or close the openings 10 and 11 in the cover member 7. These openings 10 and 11 and the opening 21 are 5 preferably of rectangular form so that as the valve 20 uncovers its port openings 10 and 11, the port area for flow of gas will be in direct proportion to the angular adjustment of the valve.

10 The valve 20 has a cylindrical hollow, opening downwardly and threaded up to and into the zone of the ports 10, 11 to receive a plug 22. Thus the plug 22 may be adjusted longitudinally of the valve, to control the maximum port opening thereof. The upper end 15 of the valve 20 is bared to receive with a tight fit the lower extremity of a spindle 23 which may have pinned connection with the valve as at 24. The spindle 23 extends through an opening 25 in the cover member 7 and thereabove beyond the upper extremity of the casing 1 as indicated.

The casing 1 is provided with an opening 26 in which is fitted the head portion 27 of a sleeve member 28, the sleeve member having a bushing portion 29 fitted in the opening 26, and therebelow a threaded extension 30. The parts last described including the valve 20 and the sleeve 28 are aligned as indicated; 20 and the opening 25 in the cover member 7 is sufficiently larger than the spindle 23 to clear the same. Thus the spindle is supported on the one end by the valve 20 and on the other by the sleeve member 28 acting as a bushing in the casing 1. A handle 31 is secured with the projecting end of the spindle 23 as by a set screw 32 and preferably the end of the spindle is slotted as at 33 in the direction of the opening in the valve 20 to indicate the 25 setting of this valve.

Within the chamber of the casing 1 is an air valve 34 having at its upper end a hub portion 35 fitting upon a cylindrical shoulder 36 of the sleeve 28, and having a spider 37 45 with a central hub portion 38 through which the spindle 23 passes. The valve 34 is secured for rotation with the spindle as by set screw 39 in the hub portion 38 thereof. The valve 34 is generally cylindrical at its periphery 50 but is interrupted as at intervals of approximately 90° to form a pair of opposed segmental skirt portions 40. Obviously the skirt portions 40, extending into the zone of the openings 3 and 4 may be moved between 55 closed position overlying the openings, and open position in which the openings are uncovered.

60 Preferably, the openings 3 and 4 are rectangular, so that the air valve will have straight line opening and closing characteristics as described for the gas valve.

65 The valve skirt portions 40 in the zone of the ports 3 and 4, are finished outside to just clear the corresponding inner cylindrical wall of the casing 1, so that there is no bearing be-

tween the valve 34 and this wall. Thus the valve 34 moves freely yet serves to substantially cut off flow between the ports 3 and 4 when in closed position.

Turned upon the threaded extension 30 of 70 the sleeve 28 is a correspondingly threaded hub portion 41 of a curtain member 42 having segmental aprons 43 fitting in the peripheral gaps between the skirt members 40. The longitudinal dimension of the aprons 43 is such 75 that they may be moved into the dome of the casing 1 above the zone of the ports 3, 4 or adjusted downwardly into this zone. Such adjustment is effected by rotation of the head 27 of the sleeve 28.

About the spindle 23 between the spider hub 38 and the cover member 7 is a compression spring 44, which serves to maintain the valve 20 seating upwardly against the cover member 7, thus preventing escape 85 of gas upwards between the two valve chambers.

A washer 45 is arranged at the extremity of the extension 30 of the sleeve member 28. The spider hub 38 has a cavity 46 forming 90 an annular groove above the spindle 23. In this groove is positioned a compression spring 47 which bears upwardly upon the washer 45 to maintain the sleeve member 28 bearing against the hub portion 48 of the 95 handle member 31.

It will be apparent that by manipulation of the handle 31 the flow of both air and gas may be simultaneously controlled between substantially zero and maximum limits. 100 Also, the maximum air flow may be adjusted at any time independent of the seating of the handle 31 and of the adjustment of the gas valve, by rotation of the head 27. Likewise, by removal of the cap 9 and adjustment of the plug 22 the maximum gas flow may be adjusted independent of the seating of the handle 31 and of the air valve. And air or gas flow may be adjusted as to maximum without interruption to service of the 110 proportioning control unit.

115 It will be further noted that by the arrangement described no explosive mixture is present anywhere in the system up to the burner nozzle itself; and this will be true whether a single nozzle as shown, or a number of nozzles by the usual manifolding arrangement, be employed.

What we claim is:

1. A proportioning control unit for a gas 120 burner comprising a casing having a cavity with inlet and outlet openings and a mouth, a cover for said mouth, said cover having a cavity with inlet and outlet openings and a mouth, and a cap for said last named mouth, whereby casing means are had, having a pair of chambers and inlet and outlet openings for each chamber, one of said chambers being adapted for arrangement in the air supply to said burner and the other chamber 125 130

for arrangement in the gas supply line thereto, valve means in each chamber for controlling flow between said openings thereof, and means connecting said valve means for simultaneous operation.

2. A proportioning control unit for a gas burner comprising casing means having a pair of chambers with inlet and outlet openings for each, valve means in each chamber for controlling flow between said openings thereof, said casing means including a wall between said chambers, said wall having an opening, a stem extending through said wall opening to connect said valve means for simultaneous operation, and spring means arranged to maintain one of said valve means seated upon said wall about said opening to prevent flow between said chambers.

3. A proportioning control unit for a gas burner comprising casing means having a pair of chambers with inlet and outlet openings for each, valve means in each chamber for controlling flow between said openings thereof, said casing means including a wall between said chambers, said wall having an opening, a stem extending through said wall opening to connect said valve means for simultaneous operation, and spring means arranged in one of said chambers and associated with said stem to cause the valve means in the other chamber to bear upon said wall about said opening to prevent flow between said chambers.

4. A proportioning control unit for a gas burner comprising casing means having a pair of chambers with a separating wall therebetween and inlet and outlet openings for each chamber, one of said chambers being adapted for arrangement in the air supply to said burner and the other chamber for arrangement in the gas supply line thereto, valve means in each chamber for controlling flow between said openings thereof, and means extending through said wall and connecting said valve means for simultaneous operation, said wall providing a seat for one of said valve means.

5. In a proportioning control unit of the class described, casing means having a cylindrical air chamber and lateral inlet and outlet openings thereto whereby the chamber may be arranged in the air supply to a gas burner, cylindrical valve means of less diameter than that of said chamber arranged in said chamber for coaxial adjustment to control said openings, and means for supporting said valve means to clear the walls of said chamber, whereby the same will move freely between open and closed positions.

6. A proportioning control unit for a gas burner comprising casing means having a pair of cylindrical chambers and lateral inlet and outlet openings for each chamber, one of said chambers being adapted for arrangement in the air supply to said burner

and the other chamber for arrangement in the gas supply line thereto, cylindrical valve means in each chamber for controlling flow between said openings thereof, means connecting said valve means for simultaneous operation, said air valve means being of less diameter than its chamber, said gas valve means being arranged for supporting said air valve means to clear the walls of its chamber.

7. A proportioning control unit for a gas burner comprising casing means having a pair of cylindrical chambers and lateral inlet and outlet openings for each chamber, one of said chambers being adapted for arrangement in the air supply line to said burner and the other chamber for arrangement in the gas supply line thereto, cylindrical valve means in each chamber for controlling flow between said openings thereof and having ports adapted for registry with said openings for allowing said flow, means connecting said valve means for simultaneous rotational operation, and for each valve, means movable longitudinally thereof for adjustment of its maximum effective port area independently of the other and without interruption to the flow therethrough.

In testimony whereof we hereby affix our signatures.
